UNITED STATES PATENT OFFICE

WILLIAM S. MADICK, OF KANSAS CITY, MISSOURI

CORNER METAL SLIDE STRIP

Application filed April 7, 1931. Serial No. 528,412.

The present invention relates to a movable or sliding metal corner and its prime object is to prevent the drawings, wrinkling and breaking of wall decorations in case of any movement of a wall and is intended to be placed and secured by nails or screws on the surface of plaster, wood or walls of any other material before decorating.

Another very important object of the invention resides in the provision of corner metal slide strips of this nature which are exceedingly simple in their construction, inexpensive to manufacture, thoroughly efficient and reliable in use and otherwise well adapted to the purpose for which they are designed.

With the above and numerous other objects in view as will appear as the description proceeds, the invention resides in certain novel features of construction, and in the combination and arrangement of parts as will be hereinafter more fully described and claimed.

In the drawings:

Figure 1 is a top plan view of a plurality of the strips.

Figure 2 is a sectional view taken substantially on the line 2—2 of Figure 1.

Figure 3 is a perspective view of one end of one strip, and

Figure 4 is a perspective view of one end 30 of the other strip.

Referring to the drawings in detail it will be seen that the numeral 5 denotes one strip and the numeral 6 the other strip. The strip 5 has on one longitudinal edge a right angularly extending flange 7 terminating in an inwardly disposed flange 8 at right angles to the flange 7 and parallel to the strip 5 and merging into an inturned flange 9 at right angles to the strip 5 and the flange extension 8 and terminating in spaced relation to the strip 5. On one longitudinal edge of the strip 6 there is formed a right angularly extending flange 10 which merges into an inwardly directed flange extension 11 parallel with the strip 6. The flange extension 11 is adapted

to slide between the flange extension 9 and the flange 7 thereby interlocking the strips 5 and 6 together so that the strips are disposed at right angles to each other. Thus the strips are fitted in the corner one being nailed to one wall and the other being nailed to the other wall. Of course any suitable fastening means may be used.

From a consideration of the drawings, it will be readily appreciated that if either wall forming one of the corners illustrated should settle then the strip attached thereto will slide with the settling wall and therefore if the wall paper, fabric decoration, or the like is butted in the corner over the movable metal in-corner it will not draw, wrinkle or break the decorations and the same applies if painted over.

This structure will also prevent breaking of decorations if one wall moves slightly outwardly.

It is thought that the construction, utility and advantages of this invention will now be quite apparent to those skilled in this art without a more detailed description thereof.

The present embodiment of the invention has been described in considerable detail since in actual practice it attains the features of advantage enumerated as desirable in the statement of the invention and the above description.

It will be apparent that changes in the details of construction may be resorted to without departing from the spirit or scope of the invention as hereinafter claimed or sacrificing any of its advantages.

Having thus described my invention, what I claim as new is:

An in-corner retainer for wall decorations, comprising a pair of substantially flat, angularly disposed strips adapted to be respectively fixedly secured to the angularly arranged walls of a corner and to have applied thereover separate wall decorations butted in the corner, said strips having interlocked

edge portions allowing sliding movement of one strip with respect to the other whereby damage to the wall decorations by relative movement of the walls will be prevented,
5 said interlocked edge portions being disposed at the inner side of one strip whereby the two strips present entirely plane outside surfaces intersecting at an angle so that the wall decorations abut each other.

10 In testimony whereof I affix my signature.

WILLIAM S. MADICK.
